UNITED STATES PATENT OFFICE.

EDWARD BEACH GALLAHER, OF PHILADELPHIA, PENNSYLVANIA.

DESIGN FOR A MOTOR-VEHICLE FRAME.

SPECIFICATION forming part of Design No. 35,210, dated October 22, 1901.

Application filed August 15, 1901. Serial No. 72,195. Term of patent 7 years.

To all whom it may concern:

Be it known that I, EDWARD BEACH GALLAHER, a citizen of the United States, and a resident of Philadelphia, in the county of Philadelphia and State of Pennsylvania, have invented and produced a new and original Design for a Motor-Vehicle Frame, of which the following is a specification, reference being had to the accompanying drawing, forming a part thereof, in which the figure shows a plan view of the motor-vehicle frame.

As shown in the drawing, the leading or material feature of my design is in the configuration of a motor-vehicle frame formed by side bars *a* and *b*, having their front ends developed into a straight front cross-bar *c* by curved elbows *h* *i*, the said side bars being

spread apart about midway their lengths, the said spread portions being spaced apart by a rear straight cross-bar *d* and an intermediate straight cross-bar *e*, the said side bars having straight extensions *f* and *g* projected beyond the rear straight cross-bar *d*.

What I claim is—

The design for a motor-vehicle frame, substantially as herein shown and described.

In testimony that I claim the foregoing as my invention I have signed my name, in presence of two witnesses, this 2d day of August, 1901.

EDWARD BEACH GALLAHER.

Witnesses:

Wm. R. WOOTERS,
Hy. A. STONE.
